SHAFT COUPLING MECHANISM FOR INTERNAL COMBUSTION ENGINES

Hans Davids, Beloit, Wis., assignor to Fairbanks, Morse & Co., Chicago, Ill., a corporation of Illinois

Application June 27, 1940, Serial No. 342,626

2 Claims.

(Cl. 64—13)

This invention relates to improvements in shaft coupling mechanism for internal combustion engines of opposed piston type, characterized by crankshafts at the opposite ends of the cylinders, and has particular reference to an improved mechanism of bevel gear type, providing a power-drive coupling of the engine crankshafts.

An important object of the invention resides in the provision in an engine of the character indicated, of an improved bevel gear coupling mechanism of great strength, serving to interconnect the engine crankshafts in a torsionally rigid manner, whereby to effect the desired power transmission between the crankshafts, the improved coupling further being fully adjustable to provide for variations in the phase relationship of the crankshafts.

Another object of the invention consists in the minimization of housing structure for the coupling assembly, particularly the minimization or elimination entirely of the more heavy and bulky housing elements heretofore sometimes utilized, apart from the engine frame structure itself. The attainment of this object in the elimination of bulky housings for the gears and shafting, renders available a greater space for the shaft and gear elements, enabling the use, with less overall space requirements, of considerably heavier shafting and gear elements, as well as making for considerable economy in the weight of structure utilized in carrying out the present improvements.

Numerous other objects and advantages attending the present invention, will appear readily from the following description of a preferred embodiment of the invention as disclosed by the accompanying drawings, wherein the improved coupling is illustrated as applied to a vertical opposed piston engine, although it is to be understood that the coupling is readily applicable to horizontal engines.

In the drawings, Fig. 1 is a fragmentary longitudinal section as taken vertically through an internal combustion engine of the character herein indicated, illustrating in assembly, a preferred form of bevel gear coupling between the upper and lower crankshafts, and showing the preferred manner of supporting the coupling in the engine frame; Fig. 2 is an enlarged vertical section through the coupling assembly and the coupling zone of the engine frame, as taken longitudinally of the frame, the view clearly illustrating the details of structure and assembly of the couplings; Figs. 3, 4 and 5 are horizontal sections through the coupling mechanism, as viewed

respectively, from lines 3—3, 4—4, and 5—5 in Fig. 2; Fig. 6 is an enlarged, fragmentary vertical section through a part of the coupling, as taken along line 6—6 of Fig. 3, and Fig. 7 is a similar enlarged vertical section through the coupling, as taken along line 7—7 of Fig. 5.

Referring to the drawings by suitable characters of reference, there is shown by Fig. 1 the crankshaft coupling section or end 10 of a preferred form of internal combustion engine of the vertical opposed piston type having crankshafts at the opposite ends of the cylinders. The view of Fig. 1 is a vertical fragmentary section longitudinally of the engine, illustrating principal elements of the engine frame and cylinder-piston assembly, together with the upper and lower power shafts or crankshafts 11 and 12 respectively, and the assembled bevel gear crankshaft coupling mechanism 14 forming the subject of the invention. Although for the purpose of the present exemplary disclosure, only one cylinder and opposed piston assembly is shown, it is to be understood that the present improved coupling is applicable generally, to opposed piston engines of either single or multicylinder type. Also, the coupling is readily applicable to engines of the vertical or horizontal type.

Describing generally the engine frame structure and the crankshaft and cylinder-piston organization supported thereby, the frame includes principal vertical members longitudinally spaced intermediate the ends of the frame, two thereof 15 and 16 being shown in the present example, and end plates or members one of which is shown at 17. Vertically spaced, horizontal deck-forming members or plates 18, 19, 20 and 21 extend longitudinally and laterally in the cylinder-containing portion of the frame, and certain of these deck plates, as 18, 19 and 21, are projected to the vertical end plate 17. The several deck plates which bear in assembly, a structurally interfitting relation with the vertical members 15 and 16, are apertured centrally in the zones thereof between the vertical frame members 15 and 16, as at 22, such that the apertures are in vertical axial registry, for the reception therethrough of a suitable cylinder liner 23. Opposed pistons 24 and 25 operate in the cylinder liner as shown, the upper piston 24 being operatively connected to the crank 26 of the upper crankshaft 11 through connecting rod 27, and the lower piston 25 being similarly connected through a connecting rod 28, to the crank 29 of the lower crankshaft 12. The upper crankshaft is journaled in suitable bearings 30, 31 and 32 carried respectively, by the

upper ends of the vertical frame members 15 and 16, and the end plate 17, while the lower crankshaft is similarly journalled in bearings 33, 34 and 35 carried respectively, by the lower ends of the members 15 and 16, and the end plate 17. The cylinder block or frame assembly according to the foregoing brief description, may be and preferably is of the form and construction fully set out in detail, in a copending application by James W. Owens and Hans Davids, for Engine frame construction, filed August 28, 1939, and bearing Serial No. 292,231, said application now being Letters Patent No. 2,246,857, issued June 24, 1941.

Operatively associated with the upper crankshaft 11 on the portion thereof spanning the vertical frame members 16 and 17, is a bevel gear 40. In the present example and as appears in Fig. 2, the gear 40 is of ring type, secured by bolting as at 41, to a flange 42 preferably formed integrally with the crankshaft near the shaft journal bearing 31. As a means for minimizing or substantially preventing longitudinal or axial displacement of the crankshaft relative to the frame structure, the bearing 31 is annularly and outwardly flanged at its ends, as at 43 and 44, and is axially extended as shown, such that the flanged end 43 substantially abuts the flanged portion 45 of the crank 26, while the opposite flanged end 44 of the bearing substantially abuts the gear-connecting flange 42 of the crankshaft. Further, the bearing is channeled intermediate its ends, as at 46, to closely receive the bearing-supporting structure or backing 47 which is fixedly carried by the upper end of the vertical frame member 16. Thus, in this manner as will now appear, the crankshaft is substantially confined against endwise or axial displacement movement, except to the slight degree permitted by a minimum working clearance relative to the bearing.

A bevel gear 48 is operatively secured to the lower crankshaft 12 in a manner similar to the gear 40 on the upper shaft, and according to the arrangement of the present example, the gear 48 is located on the shaft such as to be disposed in the vertical plane of the upper gear 40. Also, the lower crankshaft is limited or confined against endwise or axial displacement through the bearing 34, in like manner as hereinabove described for the upper crankshaft.

Turning now to the structural features and mounting arrangement of the improved coupling mechanism 14, as provided for positive and synchronous power transmission connection of the upper and lower crankshafts, the upper deck plates 18 and 19 are each apertured as at 50 and 51 respectively, centrally in the portions thereof extending between the vertical frame members 16 and 17. These apertures which are preferably circular in form and in vertical axial registry, are provided to receive therethrough, a journal housing 52 for a vertical shaft element 53 (Fig. 2). Arranged concentrically of the deck plate aperture 50, is a ring or collar 54 which may be secured, as by welding, to the deck plate on the upper surface thereof. The housing 52 is provided near its upper end 55, with an externally projecting flange 56 which in the assembly of the housing to the frame, bears upon the ring 54, and at its lower end 57, with an external annular boss 58 which seats snugly in the aperture 51 in deck plate 19 (Fig. 2). The housing is rigidly secured to the frame preferably through a plurality of studs 59 each threadedly seated in the ring 54 and

deck plate 18 (Figs. 3 and 6), and projecting upwardly through stud openings 60 in the housing flange 56. Suitable nuts 61 threaded onto the projecting ends of the studs, serve when drawn up, to effectively clamp the housing to the deck plate 18.

The shaft element 53 which extends vertically and centrally through the housing 52 (Fig. 2), is rotatively journalled therein by a suitable roller bearing assembly 70 carried in the upper end portion 55 of the housing, and a suitable thrust-bearing 71 of roller type, located in the housing lower end section 57. According to the presently preferred construction, the outer race element 72 of the upper bearing 70 is snugly entered into the upper end 55 of the housing and bears upon an annular internal housing flange 73, while the outer race 74 of the lower bearing 71 is similarly received in the lower end of the housing and held in place by confinement between an annular internal housing flange 75 and a flanged ring or collar 76 preferably removably secured to the lower end of the housing. The inner race 77 of the upper bearing engages the shaft 53 inwardly of its upper flanged or headed end 78, and seated upon the shaft end between the inner race 77 and the shaft head or flange 79, is a beveled pinion 80 which enmeshes with the beveled gear 40 on the upper crankshaft 11. The pinion as shown, is secured to the shaft 53 by a suitable key connection 81. The inner race 82 of the lower bearing 71 engages the shaft upwardly or inwardly of its lower tapered end 83, while the relative vertical spacing of the inner races of both bearings 33 is maintained by a tubular spacer member 84 sleeved upon the shaft and having its ends engaging or abutting the inner races in the manner clearly shown by Fig. 2. Further, the shaft below the lower bearing and inwardly adjacent the lower tapered shaft end is threaded to receive a washer and lock-nut assembly 86 which when drawn up, securely clamps the inner bearing races 82, 77, spacer sleeve 84 and pinion 80 between the locknut and the shaft head flange 79. From this arrangement it will be observed now that the shaft 53 through the bearing assemblies, is operatively supported by and suspended with respect to, the housing 52, in a definite vertical position relative to the housing. In other words, the shaft rotatively journalled as described, is thereby substantially precluded against vertical or axial displacement relative to the housing, and hence relative to the frame plates 18 and 19 through the rigid securing of the housing 52 to the deck plate 18, as before described. Also, from the particular manner of journalling the shaft 53, any lateral displacement of the shaft relative to the housing 52, is thereby effectively precluded.

The lower deck plate 21 is centrally apertured at 90, in the portion thereof extending between the vertical frame members 16 and 17, to receive therethrough a journal housing 91 for a second vertical shaft element 92. The assembly arrangement and location of the lower housing and shaft is such that the axis of the lower shaft 92 normally will be in vertical registry with the axis of the upper shaft 53, as indicated by Fig. 2, in order to facilitate coupling of the shafts by means later to be described. The housing 91 which may be somewhat similar to the upper housing 52, is provided with an external circumferential flange 93 through which the housing is rigidly secured to the deck plate 21, as by studs 94 and clamping nuts 95 (Figs. 5 and 7).

Interposed between the housing flange and deck plate is a ring or collar 96 which may be secured to the deck plate preferably by welding. The foregoing described support of the lower housing on the deck plate 21 is substantially like that provided for the upper housing 52, as will now appear. Since in the present example, the lower end portion 97 of the lower housing 91 is not retained against lateral stress displacement by direct engagement with an element of the frame, as in the case of the upper housing 52 having its lower end seated in the aperture 51 in deck plate 19, provision is made for preventing such displacement, by a tubular member 98 sleeved over the housing and secured at its upper end, as by welding, to the under side of the deck plate 21. The lower end of the sleeve 98 is engaged by an annular boss 99 on the lower end 97 of the housing, as appears in Fig. 2. Thus the member 98 serves in conjunction with the flange and collar connection 93-96, to maintain the lower housing 91 in proper assembly position relative to the frame deck 21. It is to be noted that the housing assembly 91 is readily removable without disturbing the lower crankshaft 12, as by upward displacement through the deck plate 21, and thence laterally of the engine frame and outwardly through a frame opening provided therefor (not shown).

Journalling of the shaft 92 in the housing 91 is effected in a manner similar to that provided for the operative support of the upper shaft 53 in its housing 52. Accordingly, a suitable thrust-bearing 100 of roller type, is mounted in the upper end section 101 of the housing, while a roller bearing 102 is arranged within the lower end 103 of the housing. Keyed as at 104, to the lower headed end 105 of the shaft, is a bevelled pinion 106 which enmeshes with the bevelled gear 48 on the lower crankshaft 12. As in the case of the upper shaft assembly, the pinion 106, inner race 107 of the bearing 102, a bearing spacer member 108 sleeved on the shaft, and the inner race 109 of the bearing 100, are clamped between the terminal flange 110 on the lower shaft end 105 and a washer and lock-nut assembly 111 received on the upper end of the shaft, inwardly of the upper tapered end 112 thereof. Thus the shaft 92 is thereby rotatively supported by the housing 91 in a manner similar to the support of the upper shaft 53, as to substantially preclude vertical and lateral displacement thereof relative to the housing, and hence relative to the deck plate 21, as will readily appear.

The tapered ends 83 and 112 of the shaft elements 53 and 92 respectively, as shown by Fig. 2, are in opposed, vertical alignment, and suitably axially spaced to accommodate a flexible or semi-flexible shaft-coupling assembly denoted generally, by the reference character 120. The coupling 120 may be of a well known construction providing for torsional rigidity of shaft connection, while permitting some relative axial displacement of the shafts coupled thereby, the coupling serving also, in the torsionally rigid connecting of the shaft elements thereby, to provide for axial misalignment of the shaft elements. As here shown, the coupling includes a sleeve or collar 121, the bore 122 of which is tapered to provide for the reception of the sleeve on the tapered end 83 of the upper shaft 53. The sleeve is effectively retained on the shaft by a suitable lock-nut assembly 123 on the terminal-end of the shaft, and is secured for rotation with the shaft as by the key connection 124. As appears

in Figs. 2 and 4, the lower end of the sleeve is flanged to provide diametrically opposed, laterally projecting wings or ears 125, and to these ears is secured as by the bolts 126, a ring member or annulus 127. The member 127 which is comprised of a suitable number of elements or laminae 128, as illustrated, is further connected to a tubular member 129 forming a part of the coupling assembly, through diametrically opposed flange-ears 130 formed on the upper end of the member 129, as shown by Fig. 1 and in broken lines by Fig. 4. Suitable bolts 131 provide the connection of the annulus 127 to these ears 130. As appears in Fig. 4, the member 129 is arranged such that its opposed ears 130 bear substantially a right-angle relation to the opposed ears 125 of the sleeve 121, so that the laminated member 127 is thereby alternately connected to the ears 125 and 130 at points on the member which are angularly spaced by substantially ninety degrees or a right angle. As a result, the laminated annulus 127 connected to the sleeve 121 and member 129 in the manner described, provides a torsionally rigid connection of the latter elements, and yet permits of a minimum but appreciable relative axial displacement of these elements, which factor will be hereinafter more particularly referred to.

The lower end of the member 129 is similarly flanged to provide diametrically opposed ears 135, the lower set of ears 135 however, being angularly displaced relative to the upper set 130 on the member, by substantially ninety degrees. Secured to these ears 135, as by the bolts 136, is a second laminated annulus 137 which may be in all respects, like that of the first described annulus 127. The annulus 137 further, is secured as by bolting, to diametrically opposed ears, one of which is shown at 138 in Fig. 1, on the upper end of a tapered collar 139. The lower sets of ears 135 and 138 bear the same relative relation to the annulus 137 as described for the upper sets of ears 125 and 130 relative to the annulus 127.

The bore 140 of the collar 139 is tapered as shown by Fig. 2, to provide for seating of the element upon an externally tapered member or sleeve 141. The sleeve 141 has its bore tapered to accommodate the upper tapered end 112 of the shaft 92, upon which it is retained by a lock-nut and washer assembly 142, the sleeve further being secured to the shaft for rotation therewith, as by the key connection 143.

For reasons well understood in the art, it is desirable in connection with engines of the type hereinabove described, to make suitable provision of a character enabling relative angular adjustments of the crankshafts to be made, so that any predetermined desired phase relationship of the crankshafts may be attained. Such may be provided for quite readily and conveniently, in the structure of the crankshaft synchronizing coupling, this being accomplished in the improved coupling forming the subject of the present invention, in the assembly relation and operative connection of the collar and sleeve elements 139 and 141, as will be now described.

Referring to Fig. 2 in particular, the collar 139 is formed to provide at its lower end, an annular flange 144, while the lower end of the sleeve 141 is provided with an annular flange 145 formed to present a peripheral undercut portion or shouldered seat 146 extending about the flange. In the assembly of the collar and sleeve, these elements are connected together for conjoint rota-

tion, through the above described flanges 144 and 145, by releasable clamping means comprising a ring member 147 seating in the shouldered seat 146 of flange 145 and bolted to the collar flange 144 by a plurality of bolts 148. From the foregoing, it will be observed that the connection of the collar and sleeve for rotation as a unit, is effected through the clamping means described, by drawing up the bolts 148. This results in wedging the collar upon the tapered sleeve for securing positive frictional engagement therebetween, and further, in tightly clamping together the collar and sleeve flanges. Release of the clamping means in an obvious manner thereby disconnects the collar from the sleeve, so that one may be rotated relative to the other, as for relative angular adjustment of the coupling shaft and pinion assemblies 53-80 and 92-106 to adjust or vary the phase relationship of the two crankshafts. Following the desired phase adjustment, the clamping bolts 148 may be again drawn up to secure the collar and sleeve together as before described.

From the foregoing, it will be seen that a greatly improved crankshaft synchronizing coupling mechanism is provided, as exemplified by the preferred embodiment herein, the construction of which is relatively simple and such as to provide for a torsionally rigid connection of the crankshafts. Moreover and as will be now fully appreciated, the flexible coupling device comprised of the laminated members 127 and 137 and related elements, while providing an effective, torsionally rigid connection of the shaft elements 53 and 92, permits of limited relative displacements of the shaft elements in the axial direction, such as may result from relative displacement or warpage of the engine frame elements due to thermal expansion, operating stresses or other cause, and from thermal expansion of the shaft elements. Also and as hereinabove indicated, the flexible coupling compensates for limited axial misalignment of the shaft elements.

A feature of importance according to the present improvements, is found in the manner of supporting the coupling mechanism in the engine assembly. As herein fully described and illustrated, the coupling generally, is comprised of separate sections connected together through the laminated ring members 127 and 137, the upper section of which, as constituted by the shaft 53, pinion 80, the shaft journal housing 52 and associated parts, is independently supported by the upper frame deck plates 18 and 19. The other section as constituted by the shaft 92, pinion 106, shaft journal housing 91 and associated parts, is similarly independently supported by the lower frame deck 21. Thus such thermal expansion and warpage as may occur during engine operation, in the frame decks 18 and 19 and the vertical frame plates 16 and 17 in the zones thereof adjacent the upper coupling section and crankshaft, will affect only the said coupling section and the bevel gear connection between it and the upper crankshaft. This obtains for the reason that the laminated ring connection 127-137 between the coupling sections is of a type permitting limited axial displacement of the upper section relative to the lower coupling section, as hereinabove fully described. The same condition obtains for the lower coupling section and its bevel gear connection to the lower crankshaft. In this way then, the effect of thermal expansion and warpage of the engine frame on the coupling and its operative connection to the

crankshafts, which under extreme conditions might otherwise produce a partial disengagement, or increase the back lash, of the coupling pinions and crankshaft gears, is thereby appreciably minimized. In other words, the improved manner of mounting the coupling sections in the engine frame, is such as will effectively compensate for frame expansion and warpage, to a degree resulting in substantial maintenance of the coupling and crankshaft drive connection throughout engine operation.

Among other features of importance attending the presently improved crankshaft coupling assembly, is the simplification of the construction and mounting of the coupling such as to enable the use of coupling shaft elements of fully adequate strength, and relatively large-diameter pinions and gears characterized by gear-tooth constructions providing desirably greater back lash tolerances, such that a fully effective meshing or operative connection of the gears and pinions will obtain without any adverse effect thereon by reason of normal or even limited abnormal thermal expansion of the several parts of the coupling, the crankshaft assemblies and the engine frame. Further, the coupling assembly is desirably compact, and hence may be readily incorporated in an engine organization which provides but a limited space for a crankshaft coupling mechanism. It will be observed also, that suitable shims (not shown) may be employed to facilitate proper positionment and mounting of the coupling shaft housings 52 and 91, the shims being located between the seating ring 54 and housing flange 56 in respect to the upper housing 52, and between the similar seating ring 93 and housing flange 95 in respect to the lower housing 91. Moreover, by the use of shims as above indicated, the enmeshing conditions of the bevelled pinions and gears may be additionally controlled, as will be appreciated.

It will be understood, of course, that the foregoing description relates to the preferred embodiment of the coupling mechanism as herein illustrated, and that alterations or modifications thereof may be made without departing from the scope and intentment of the invention, as hereinafter claimed.

I claim:

1. In a mechanism of the character described for interconnecting spaced power shafts of an internal combustion engine, a pair of shaft elements in substantial axial alignment and having their opposed ends spaced apart, a coupling hub carried by one of said shaft elements and provided with radially projecting arms, a laminated annulus arranged in a plane normal to the axis of said shaft elements, means securing said annulus to said arms, a coupling member between the opposed ends of the shaft elements, said member having arms projecting therefrom at one end, means connecting said last arms to said annulus at points thereon spaced from said means securing the annulus to the arms of said coupling hub, a second laminated annulus arranged parallel to the first said annulus, arms projecting from the opposite end of said coupling member and connected to said second annulus, and angularly adjustable means securing said second annulus to the other of said shaft elements, said adjustable means including tapered, telescopically engaging elements, one thereof having a projecting annular flange at one end, and a clamping ring carried by the other tapered element for clamping engagement with said flange.

2. In a mechanism of the character described for interconnecting spaced power shafts of an internal combustion engine, a pair of shaft elements in substantial axial alignment and having their opposed ends spaced apart, a coupling member carried by one of said shaft element, a flexible, laminated annulus arranged in a plane normal to the axis of said shaft elements and secured at spaced points thereof, to said coupling member, and means for connecting said annulus from points thereon spaced from said first mentioned points of securement to said coupling member, to the other of said shaft elements, said means including an externally tapered collar member secured on said last mentioned shaft element and provided with an annular projecting

flange having a shouldered peripheral seat therein, an internally tapered sleeve member seating on said tapered collar member and formed to provide an annular flange near one end thereof, 5 a ring member adapted for seating in the shouldered peripheral flange seat of said collar member, and clamping elements spaced outwardly from the periphery of the flange on said collar member, connecting said ring member to the flange on said sleeve member, said clamping elements serving through said ring member, to effect relative displacement of said tapered collar and sleeve member into positive wedged engagement.
